Primary Examiner — Anhdao Doan*Assistant Examiner* — Mary Shannon Malley(74) *Attorney, Agent, or Firm* — Michael Best & Friedrich LLP(57) **CLAIM**

We claim the ornamental design for a test tube holding device, as shown and described.

DESCRIPTION

FIG. 1 is a perspective view of a test tube holding device in an open configuration according the present invention.

FIG. 2 is a front view of the test tube holding device of FIG. 1.

FIG. 3 is a rear view of the test tube holding device of FIG. 1.

FIG. 4 is a left-side view of the test tube holding device of FIG. 1.

FIG. 5 is a right-side view of the test tube holding device of FIG. 1; and,

FIG. 6 is a top view of the test tube holding device of FIG. 1.

The broken lines show portions of the test tube holding device that form no part of the claimed design.
